poration of Ohio

Application August 15, 1940, Serial No. 352,794

13 Claims. (Cl. 51—66)

This invention relates to improvements in surface finishing machines and particularly to machines for effecting superfinishing operations.

One of the objects of the present invention is the provision of a machine particularly adapted for producing a surface of extreme accuracy on cylindrical and conical articles, as for example, straight or taper rolls for roller bearings.

A further object of the present invention is the provision of an improved automatic machine for effecting a continuous finishing on a multiplicity of work pieces simultaneously.

An additional object of the invention is the provision of a machine of the character above set forth of extremely simple and compact form compatible with the work receiving capacity thereof.

An additional object of the present invention is the provision of improved mechanism for effecting the abrading operation as respects the work piece in a manner to minimize and balance out vibratory tendencies of the machine as an entirety which might otherwise be produced by the high speed relative movements of work and abrading members during the finishing operation.

Other objects and advantages of the present improved surface finishing machine should be readily apparent by reference to the following specification considered in conjunction with the appended drawings, and it will be understood that any modifications may be made in the specific structural details hereinafter described within the scope of the appended claims without departing from or exceeding the spirit of the invention.

Figure 1 is a plan view of one embodiment of the invention.

Figure 2 is a side elevation thereof.

Figure 3 is an enlarged section on the line 3—3 of Figure 1, illustrating the mounting of the work abrading members.

Figure 4 is a detail section on the line 4—4 of Figure 3.

Figure 5 is a section on the line 5—5 of Figure 3.

Figure 6 is a diagrammatic view of the hydraulic control circuit.

In the drawings the numeral 20 designates the bed of the machine having rising therefrom the journals 21 for spindle 22 on which is mounted the feed wheel 23 having a helical work receiving path 24 whose base is angularly disposed with respect to the axis of the spindle 22. The helical-

ly extending rib 25 intervenes the adjacent high and low points of the path as viewed, for example, in plan in Figure 1 so that a work piece, such as a tapered roll 26 designed for use in a taper roller bearing, will suitably fit within the path with its outer face disposed in a line parallel with the axis about which the feed wheel rotates. It will thus be seen that the work may be axially advanced by the pressure of rib 25 against the base thereof and will be suitably held in position for lengthwise movement of its outer face past the abrading elements such as 27 and 28.

One of the abrading units has been particularly illustrated in Figures 3, 4 and 5 of the drawings. It comprises a base plate 29 adapted to be suitably secured to the bed 20 and provided with ways guiding slide 30 which is adjustable relative to the base plate as by the positioning screw 31. Mounted in a socket 32 on slide 30 is a sleeve 33 keyed against rotation as by the screw 34. Split clamps as at 35 serve to lock the sleeve in longitudinally adjusted position.

Slidable within the bore of the sleeve is the hollow stem 36 of the abrading element unit having disposed interiorly thereof the compression spring 37 whose tension is adjustable by screw 38 mounted in cap 39 on the end of sleeve 33 and engaging abutment plug 40 for the spring.

A transverse pin 41 having its ends secured in sleeve 33 and its intermediate portion disposed in the slightly enlarged aperture 42 of the stem, retains the stem against appreciable rotation or axial movement and limits the urge of the stem in the direction of the feed wheel 23 under urge of spring 37.

The sleeve 36 is provided with a head portion 43 having opposed horizontal raceways 44 for the anti-friction bearings 45. Mounted in the space between said bearings are a pair of vibratory slides 46 and 47, each formed in their outer faces with way 48 for engagement with the adjacent anti-friction bearings of the head and having their inner faces formed with corresponding raceways 49 for the two sets of anti-friction bearings 50 which are thus interposed between the adjacent slides. It will thus be seen that the slides are themselves supported anti-frictionally within the head 43 for transverse reciprocating movement and at the same time supported for free relative movement, one with respect to the other. This movement may be effected by a combination of hydraulic and resilient actuating means, such as indicated in Figure 5 and particularly described in co-pending application Serial No. 315,510.

This comprises a hollow pin 51 projecting rearwardly of each of the slides through a transverse slot 52 in the head and in engagement with the hollow piston member 53 reciprocable in closed cylinder 54 of the head. The pin is preferably offset longitudinally of the piston 53 and interposed oppositely actuating springs 55 and 56 normally exert a centralizing action on the piston. Hydraulic pressure introduceable as through conduit 87b in a manner hereinafter described is coupled with piston head 53.

Means are provided for creating hydraulic pulsations in the line 87b. Each of the positive pulsations will tend to urge the associated piston downwardly as viewed in Figure 5 compressing spring 55. Release of the positive pressure spring 55 will tend to expand shifting of piston and associate slide in a reverse direction while spring 56 provides a cushioning effect, preventing hammering or undue vibration of the parts.

Each of the slides 46 and 47 is provided with a seat to receive an abradant element, such as 27 and 28. These elements are similar in general form but oppositely disposed so as to provide a substantially V-block effect in which their beveled faces 59 and 60 suitably engage the outer face of the taper roll or work piece 26. Each of the abrasive members is preferably provided with a transverse aperture 61, communicating through the passage 62 in the hollow piston actuated pin 51 with conduit 63 for the cutting fluid so that this fluid may be delivered by way of the tool to the work piece substantially at the point of relative engagement, assuring adequate lubrication of the parts and thus proper performance of the abradant action during the finishing operation.

As has been previously referred to, the present machine is intended for the performance of a final or what is known as a superfinishing operation on tapered or similar work pieces, the rotation of the feed wheel serving to take a work piece from the discharge spout 64 of the automatic hopper mechanism 65 and carry the same into the V formed by the faces 59 and 60. This hopper mechanism does not of itself form any part of the present invention but may, for example, be of the type shown in United States Patent No. 1,814,279. Due to the V formation of throat receiving the work piece it is unnecessary to employ additional work rest or other work supporting mechanisms. The continued rotation of the feed wheel will impart a slow longitudinal movement of the work past the several abrading members which may be of the same grit and grade, or progressively finer as the work approaches the discharge portion of the machine. At the same time, the rolling engagement between the surface of the feed wheel and the inner engaging portion of the work on account of the pressure of the work thereagainst through the action of springs 37 on the abrading members causes the feed wheel frictionally to engage and positively rotate the work at a uniform rate. It will thus be seen that the work is given a rotative as well as axial advancing movement with respect to the abrading members, while these members, in turn, are given a relatively high speed reciprocating movement.

This principle of operation for producing an ultimate highly accurate finish on hardened steel or other work pieces is well understood in that it is essential for satisfactory results that a multiplicity of relative movements be effected between the surface being operated upon and the abrad-

ing members at a speed adequate to effect removal of any high points or minute protuberances on the work resultant from previous machining operations and that at the same time the resultant combined speed of movement be at a sufficiently slow rate so that a true cold cutting is effected, preventing generation of heat tending to weld together the minute metallic particles removed in a manner to produce built-up edge or other effects on the abrading members which will cause scratching of the work.

Additionally, it is highly important that a sufficient flow of cutting fluid of proper grade be effected so that a protective film may eventually be produced on the surface of the work which will limit the cutting action of the abrading elements as the surface tends to be reduced to a plane and prevent stock removal or scratch formation below that plane.

One type of actuating mechanism particularly adaptable for utilization in conjunction with the form of the invention shown is diagrammatically illustrated in Figure 6. As there shown, there is provided a tank or reservoir 66 for hydraulic medium from which fluid is withdrawn by a pump 67 and discharged under pressure through conduit 68, a relief valve 69 limiting the pressure and permitting escape of unused volume of the medium.

Line 68 is coupled with distributor 70 from which a multiplicity of conduits 71, 71a, 71b, 71c, 71d and 71e extend to the cylinders 72 of the hydraulic motor 73. The cylinders have the pistons 74 provided with rollers 75 reacting on cam 76 carried by the rotor 77 of the hydraulic motor. An exhaust passage 78 in the distributor 70 is coupled through groove 79 with conduit 80. The rotor 77 is grooved in the conventional manner alternately to connect the several leads 71 with pressure conduit 68 and exhaust conduit 78 so that the motor will be suitably driven by pump 67.

The rotary shaft 77 extends through the pump casing sections 81—82 where it is provided with suitably shaped cams 83—84 for actuation of rollers 85 on the pump pistons 86. The several chambers for these pistons are individually coupled as by conduit 87 with an abrasive head 43.

As shown in the drawings the conduit 87 has a branch 87a coupled to the lower piston of the head and a second branch 87b oppositely coupled to the upper piston. By this arrangement at each compression stroke the fluid contained in the associate pump chamber is forced into the right hand end of one abrading element control cylinder and the left hand end of the associate abrading element control cylinder so that their pistons and thus the abrading elements are simultaneously equally but oppositely pressure actuated.

Correspondingly, as the roller 85 moves to the low point of cam 83 the expansion of springs 55 yieldingly reversely oppositely shift the two related abrading elements. By this method of operation oppositely acting abrading strokes are performed on the work piece causing an equalization of any cut pressures which might otherwise tend to effect axial movement of the work in one or the other direction and at the same time when effected at relatively high speeds the equal and opposite movement of the pair of abrading elements in the head tend to balance out any tendency to produce undesirable vibrations in the machine which might otherwise impair the accuracy of resultant finish produced.

It will be noted that the exhaust conduit 80

from the motor for actuation of the abradant element oscillating pump, has been shown as coupled to one side of a second hydraulic motor 88 which is coupled with the feed or regulating wheel 23 for effecting constant and uniform rotation of this wheel and by the manner of series coupling of the parts at a rate directly proportional to the rate of vibration of the abrading elements.

The return conduit 89 from the pump 88 extends through a rate determining throttle 90 and low pressure maintenance valve 91 to reservoir. Additionally coupled with this reservoir is a suction pump 92 which forces the hydraulic medium through a suitable filter 93 into conduits 94 and 95. A pressure controlled valve 96 controls the flow of medium through conduit 97 to the individual conduits 98 coupled with respective conduits 63 in the heads 43 for projecting the cutting medium to the face of the abrading elements. Individual valves 99 may be provided for controlling the flow of medium to the individual points of utilization. Conduit 95 has multiple branches 100, each controlled by a check valve 101 which are in turn coupled by the conduits 102 with the discharge conduits 87 of the abrading element vibrating motors. The check valves in these lines operate in a manner to make the lines completely closed during the compression strokes of the pistons 86 but permit their opening for filler replacement purposes during the suction stroke of the respective pistons to compensate for any possible leakages.

The structure and controls just described are capable of utilization in various manners for satisfactory accomplishment of the desired finishing operation.

In Figures 1 and 2 the feed or regulating wheel 23 has been shown as disposed in a horizontal position with opposed abrading elements at the front and rear of the machine so that two lineal paths on the wheel are effective at one time for transfer of the work piece from the receiving or hopper end of the machine to the discharge end.

From the foregoing it will be noted that there has been provided an extremely efficient machine for performance of a finishing operation of high accuracy simultaneously on a multiplicity of work pieces of frustro-conical or like form in which a feeding and regulating wheel having a helical path or transverse configuration corresponding to the general form of work piece may be coupled satisfactorily for controlled presentation of a multiple series of work pieces to high speed oscillating abrading elements.

It will further be noted that there has been provided a mechanism for effecting balanced or equal opposite relative movements of the abrading elements, creating a multiple break-up effect of abrading path with respect to the work and at the same time counterbalancing the thrust of the abrading elements against the work in a manner tending both to minimize general vibratory effects as respects the machine which might interfere with accuracy of the final finished product thereof. At the same time, these balanced effects of the abrading members in an individual head cause equal and opposite reactions on the work piece so that there is no sequential opposite directional drags tending to cant the work piece or disturb its proper relationship in the configurated path of the feed wheel.

It will be particularly noted by reference to Figure 1 that where a multiple number of juxtaposed abrading elements are employed that

these elements are of size to overlap a plurality of coils or windings of the helical path on the feed wheel for continuous engagement with an individual work piece as it is advanced along the path and simultaneous engagement with a plurality of consecutive work pieces; and that in addition, the juxtaposition members are so disposed that one will firmly engage and retain an individual work piece before it has left the grip of the other so that the entire series may readily flow through the machine and all liability of canting or tilting of individual work pieces is prevented.

From the foregoing it will be seen that we have provided an improved method of producing an extremely accurate or superfinished surface on frustro-conical or taper rolls for anti-friction bearings or the like articles consisting in automatically positioning the work piece and in suitably supporting it for non-axial rotation in a manner tangentially to present one or more radial planes of the work piece to the action of a rapidly vibrating abrading element while frictionally controlling the rotation of the work with respect to said element and yieldingly effecting the operative engagement of the abrading and frictional rotating elements with the interposed work piece.

What is claimed is:

- 30 1. A machine of the character described including a contoured wheel having a helical path formed therein for reception of work pieces, the contour of the path being such as to present the outer face of a series of work pieces in substantially continuous line, means providing divergent work engaging surfaces in the form of a V-block for engagement with said outer surface of the work pieces, one of said work engaging surfaces being formed of abrasive material to provide an abrading member, means for resiliently maintaining the abrading member in engagement with the work pieces, means for effecting rotation of the wheel to successively advance the series of work pieces past the member, means for effecting high speed oscillation of the member during such traversing movement, means for synchronizing the relative rate of said traversing and oscillatory movements, and means for proportionately varying the rates of actuation of the feeding wheel and abrading member.
- 35 2. A machine of the character described including a feed wheel having a contoured helically wound path formed on the periphery thereof for reception of a series of contoured work pieces, a helical work feeding rib intervening the convolutions of the path and effective on rotation of the wheel for imparting feeding movement to said work pieces, an abrading member disposed in opposition to the feed wheel and comprising a pair of beveled elements, together providing a work receiving V supporting and retaining the work within the contoured path on the feed wheel, means for effecting rotation of the feed wheel to traverse work pieces in the path past the abrading element, means for effecting oppositely phased high speed vibration of the abrading elements in engagement with the individual work piece whereby said abrading elements have equal and opposite reactions on the work piece during the feeding movement thereof, intercoupled drive means for maintaining synchronized relationship between the rate of rotation of the feed wheel and the rates of oscillation of the abrading members, and means for proportionately varying both of said rates.

3. A machine of the character described including a controlling member in the form of a wheel having a helical transversely contoured work receiving path, means for delivering work pieces into said path at a plurality of stations circumferentially of the wheel to form two lines of work pieces extending parallel to the wheel, a series of abrading elements for each line of work having divergent faces providing work receiving troughs, means to rotate the wheel to effect rotation of the work pieces and progression thereof along said troughs, and means for effecting individual oscillations of the abrading elements with respect to the progressing work pieces.

4. A machine for reducing the irregularities resulting from previous machining operations on a work piece to produce a substantially plane surface including an element in the form of a wheel having an advancing helical path formed circumferentially thereon, complementary in cross section to the shape of the work pieces to be operated upon and angularly disposed in an axial direction whereby the projecting surfaces of a series of work pieces will be lineally aligned and maintained in definite axially spaced relation, means for effecting rotation of the wheel to impart an advancing rotary movement to said work pieces, a plurality of aligned abrasive elements disposed for sequential engagement with the axially advanceable work pieces, said abrasive elements being of length to overlap adjacent axially spaced work pieces, means to yieldingly urge said elements into engagement with the work pieces, and means individual to the respective abrading elements for imparting independent vibratory movements thereto.

5. A machine for reducing the irregularities resulting from previous machining operations on a work piece to produce a substantially plane surface including an element in the form of a wheel having an advancing helical path formed circumferentially thereon, complementary in cross section to the shape of the work pieces to be operated upon and angularly disposed in an axial direction whereby the projecting surfaces of a series of work pieces will be lineally aligned and maintained in definite axially spaced relation, means for effecting rotation of the wheel to impart an advancing rotary movement to said work pieces, a plurality of aligned abrasive elements disposed for sequential engagement with the axially advanceable work pieces, said abrasive elements being of length to overlap adjacent axially spaced work pieces, means to yieldingly urge said elements into engagement with the work pieces, means individual to the respective abrading elements for imparting independent vibratory movements thereto, and means for proportionately varying the operating speeds of rotation and vibration as respects the wheel and abrading elements.

6. A machine for reducing the irregularities resulting from previous machining operations on a work piece to produce a substantially plane surface including an element in the form of a wheel having an advancing helical path formed circumferentially thereon, complementary in cross section to the shape of the work pieces to be operated upon and angularly disposed in an axial direction whereby the projecting surfaces of a series of work pieces will be lineally aligned and maintained in definite axially spaced relation, means for effecting rotation of the wheel to impart an advancing rotary movement to said work pieces, a plurality of sets of aligned abra-

sive elements disposed for sequential engagement with the axially advanceable work pieces, the elements of each set being relatively movable and of length to overlap adjacent axially spaced work pieces, means to yieldingly urge said elements into engagement with the work pieces, and means individual to the respective abrading elements of each set for imparting independent oppositely phased vibratory movements thereto.

10 7. A machine for reducing the irregularities resulting from previous machining operations on a work piece to produce a substantially plane surface including an element in the form of a wheel having an advancing helical path formed circumferentially thereon, complementary in cross section to the shape of the work pieces to be operated upon and angularly disposed in an axial direction whereby the projecting surfaces of a series of work pieces will be lineally aligned and maintained in definite axially spaced relation, means for effecting rotation of the wheel to impart an advancing rotary movement to said work pieces, a plurality of sets of aligned abrasive elements disposed for sequential engagement with the axially advanceable work pieces, the elements of each set being relatively movable and of length to overlap adjacent axially spaced work pieces, means to yieldingly urge said elements into engagement with the work pieces, means individual to the respective abrading elements of each set for imparting independent oppositely phased vibratory movements thereto, and means for proportionately varying the speed of rotation of the wheel and the rate of vibration of the abrading elements.

15 8. A machine of the character described including a contoured wheel having a helical path formed therein for reception of work pieces, the contour of the path being such as to present the outer face of a series of work pieces in a substantially continuous line, a series of abrading units closely spaced along said line, each unit comprising means for providing a pair of work engaging surfaces diverging on opposite sides of 20 said line to form a work receiving trough, one of said surfaces consisting of an abrasive element, resilient means for pressing said surfaces against the work to urge the same in driving engagement with the wheel, means to effect relative high speed reciprocation of the abrasive elements, and means to effect rotation of the wheel to rotate and feed the work sequentially past said elements.

25 9. A machine of the character described including a contoured wheel having a helical path formed therein for reception of work pieces, the contour of the path being such as to present the outer face of a series of work pieces in a substantially continuous line, a series of abrading units closely spaced along said line, each unit comprising a pair of abrasive blocks having work engaging surfaces diverging on opposite sides of 30 said line to form a work receiving trough, resilient means acting on said blocks to hold the work against the wheel, means to effect opposite phased high speed reciprocation of each pair of abrasive blocks, and means to effect rotation of the wheel to rotate and feed the work sequentially past said abrasive blocks.

35 10. A machine of the character described including a contoured wheel having a helical path formed therein for reception of work pieces, the contour of the path being such as to present the outer face of a series of work pieces in a substantially continuous line, a series of abrading

units closely spaced along said line, each unit comprising a pair of abrasive elements, said elements having work engaging surfaces diverging on opposite sides of said line, resiliently operable means for urging said elements into supporting and operative engagement with the work, individual hydraulic motors for actuation of the respective elements, a source of pulsating hydraulic pressure for said motors, means connecting the motors of a pair in opposite phased relation to said source, and means to effect rotation of the wheel to feed the work sequentially past said members.

11. A machine of the character described including a contoured wheel having a helical path formed therein for reception of work pieces, means to support work pieces in said path in a substantially continuous line including a series of aligned abrading units, each unit having a pair of abrasive members, the work engaging surfaces of which diverge on opposite sides of a work piece, resiliently operable means effective on said members for urging the work into operative engagement with said wheel to a sufficient extent to cause rotation of the work, individual fluid operable motors for reciprocating each member, a source of fluid pressure for said motors, a common pulsator for transmitting pulsations through said fluid to effect vibration of said motors, and means to effect rotation of the wheel to feed the work sequentially past said members.

12. A machine of the character described including a contoured wheel having a helical path formed therein for reception of work pieces, means for supporting a first series of work pieces in a substantially continuous line parallel to the axis of the wheel, means for supporting a second series of work pieces in a substantially continu-

ous line on the opposite side of said wheel, a series of abrading units for each line of work pieces, each unit comprising a pair of abrasive elements to hold the line of work pieces in engagement with said wheel, individual fluid operable means for reciprocating the abrading elements of each unit, a common source of fluid pressure, individual pulsators for the respective series of abrading units and connected in parallel therewith, a common actuator for said pulsators, and means to effect rotation of the wheel to feed the rows of work simultaneously and sequentially past the respective series of units.

13. A machine of the character described including a feed wheel having a contoured helically wound path formed on the periphery thereof for reception of a series of contoured work pieces, a helical work feeding rib intervening the convolutions of the path and effective on rotation of the wheel for imparting feeding movement to said work pieces, means extending longitudinally of the wheel to form a work receiving trough including a series of abrading units, each unit having a pair of diverging work engaging members for holding the work in engagement with the wheel, means to feed work pieces to one end of said trough, means for effecting rotation of the feed wheel to traverse work pieces through said trough and past the abrading elements, and means for effecting oppositely phased high speed vibration of each pair of abrading elements whereby said abrading elements have equal and opposite reactions on the work piece during the feeding movement thereof.
